METHOD OF AND APPARATUS FOR MAKING
ZIGZAG OR FAN-FOLDED ASSEMBLIES OF
SERIES CONNECTED ENVELOPESVincent E. Heywood, Worcester, Mass., assignor
to United States Envelope Company, Spring-
field, Mass., a corporation of Maine

Application July 15, 1941, Serial No. 402,524

4 Claims. (Cl. 93—61)

The present invention relates to the production of zig-zag or fan-folded assemblies or chains of series-connected envelopes, in a form that meets all the exacting requirements of such "business" machines (for bookkeeping, addressing, and like purposes) as are constructed to handle and feed their entry-receiving media in a continuous web or strip which is presented to the machine as a zig-zag or fan-folded stack. To meet such requirements the envelopes or closures must be capable of ready separation from the series into individual units for subsequent loading and sealing after entry by the machine of the appropriate data thereon, and furthermore, must be capable of being fed accurately as a series, in order to insure absolutely correct registration of each envelope unit with the writing devices of the business machine.

According to my invention, a suitable cross-scored web or carry strip is continuously fed lengthwise, and at the same time the succession of spaced-apart completed envelopes, travelling in the same direction and at the same speed as said web, are brought one by one into registry and adhesive contact with the spaces between the web's cross-scores, thus to obtain a composite web-and-envelope structure which is collected or assembled in a zig-zag or fan-folded stack, of the form required for its use in a "business" machine.

The above and other features and advantages of the invention will hereinafter more fully appear from the following detailed description thereof, taken in connection with the accompanying drawings, in which—

Fig. 1 is a diagrammatic view, illustrating the essential principles and elements of my improved process and apparatus.

Fig. 2 is a view partly in section, and partly in side elevation, of a portion of the apparatus illustrated in Fig. 1.

Fig. 3 is a plan view of the mechanism shown in Fig. 2.

Fig. 4 is an end elevation of the mechanism of Fig. 1, as viewed from the right, with certain parts omitted.

Fig. 5 is a fragmentary sectional view substantially along the line Y—Y of Fig. 2, on an enlarged scale.

Fig. 6 is a plan view of a short section of the composite web-and-envelope product of my improved process and apparatus.

As shown diagrammatically in Fig. 1, the method and apparatus of my invention contemplates the use of a continuous paper web or carry strip

2, which at regular intervals throughout its length is cross-scored to provide weakened severance lines 3, so that the strip is readily foldable along these lines to form a compact zig-zag stack, conveniently arranged on a suitable support 1, with a considerable length of folded strip occupying a relatively small space, owing to the tendency of the folded portions to pack tightly. The strip 2 also provides along one edge a suitable band 4, having perforations 5 at regular intervals, the band 4 being readily removable, along a weakened line of severance 6 (see Fig. 6), after it has performed its usual function of feeding the strip through a business machine.

The continuous lengthwise movement of web or strip 2 is here shown as obtained by a feed drum 7, secured to a rotating shaft 8 and having on its periphery a circular series of pins 9 so spaced as to be freely received in the perforations 5 of the feed band 4 when the strip 2 is passed around the periphery of the drum 7. It is to be noted that the drum 7 is of such diameter that a considerable number of pins 9 are received in the perforations 5 between the points of tangency A and B, where the strip passes onto and leaves the periphery of the drum 7. In advance of its engagement with the drum 7 at the point A, the strip 2 passes between a pair of applicator rolls 10 and 11, spaced from the drum so as to maintain in a horizontal plane a section of strip, the length of which is greater than the distance between adjacent severance lines 3. In its travel between the rolls 10 and 11 and the drum 7, the strip is supported by a plate 12 (see Fig. 2), so that it cannot sag.

The web or carry strip 2 is here shown as being drawn over the roll 10 from a point below said roll, being guided in its movement toward said roll by a suitable guide 13, which receives the strip after the latter has passed over a guide bar 15 and under a guide bar 14, these guide bars being substantially in line with the support 1. The distance between the front bar 14 and the support 1 is such that the fan-folded strip is free to unfold as the strip is advanced by rotation of the feed drum 7. There is, however, no tension on the strip between the guide bar 14 and the support, so that the strip tends to sag on either side of the intermediate guide bar 15 as the unfolding progresses.

In order to prevent the unfolding action of the strip 2 from imparting a sidewise motion which might tend to cause misalignment of the strip with the feed drum, a compensating rod 16 co-operates with the guide bar 14. The ends of the

rod 18 are freely received in slots 17 provided by brackets 18, so that the rod bears on the strip and, by reason of its weight, tends to maintain a slight tension on the strip between the bar and the roll 10. In this way, the jerking action to which the strip is subjected as it unfolds, is compensated for without lateral displacement of the strip, before it enters between the rolls 10 and 11, the function of which is to apply envelopes to the moving strip by a mechanism which will 10 next be described.

As best shown in Fig. 2, the apparatus provides a second support 19 having a trough 20 of adjustable width for receiving on edge a stack of envelopes 21, having their seal flaps 21a (see Fig. 6) extended in open position, the width of each envelope being slightly less than the distance between adjacent severance lines 3 of the strip 2. The support 19 is inclined from the horizontal at such an angle that the envelopes 21 tend to slide downwardly in the trough 20 in the direction of a rotatable feed wheel 22 mounted on a shaft 23 extending parallel to the shaft 8, which carries the strip feeding drum 7. The feed wheel 22 provides grippers 24, of frictional material, and once during each revolution of the shaft 23, the grippers 24 contact the foremost envelope as supported in the trough and carry it into engagement with a roll 25 mounted on a shaft 26 extending below and parallel to the shaft 23.

The shaft 26 is driven from any suitable source of power, as by means of a pulley 27 and belt 28, with the shaft 23 being connected to the shaft 26 by gearing 29 (see Fig. 3). Normally the stack of envelopes bears loosely on the periphery of the feed wheel 22, so that once for each revolution of the shaft 23, the grippers 24 remove one envelope from the trough and carry it forward into the bite between the roll 25 and wheel 22. Since the roll 25 is travelling at the same peripheral speed as the feed wheel 22, the envelope is positively withdrawn from the stack for delivery to a horizontally moving conveyor, generally designated by the reference character 30.

As best shown in Fig. 3, the conveyor 30 comprises a pair of spaced chains 31 passing around sprockets 32 loosely mounted on the shaft 26 on opposite sides of the roll 25. The conveyor chains 31 extend forwardly, toward the drum 7 and pass around sprockets 33 which serve to maintain the upper courses of the chains in a horizontal plane substantially in line with the top portion of the drum 7, although spaced therefrom. Both chains 31 pass partially around sprockets 34 mounted on a shaft 35, driven from the shaft 23 through a chain 36 and sprockets 37, with the ratio between the sprockets 37 being such that the conveyor 30 travels at a speed less than that of the feed wheel 22.

Certain links of the conveyor chains 31 carry transversely aligned pairs of lugs or projections 38, said pairs of projections being equally spaced apart a distance greater than the width of an envelope 21, and substantially the same as the distance between strip-severance lines 3. Consequently delivery of the envelopes one-by-one to the conveyor 30 by rotation of the feed wheel 22 and its cooperating roll 25 results in uniform spacing of the envelopes 21 on the conveyor between the lugs 38. Since the surface speed of the conveyor is less than the delivery speed of an envelope, the lugs 38 serve initially as gauges against which the leading edge of each envelope is pressed, to square up the envelope as it passes onto the conveyor. In order to prevent an en-

velope from following around the feed wheel 22, a guide 39 is mounted beside the feed wheel 22 which serves to hold the envelope in engagement with the lugs 38 until after the trailing edge of the envelope has left the bite of the feed wheel 22 and its cooperating roll 25. When once clear of the feed wheel, each envelope is carried forward by the conveyor, with its trailing edge engaged by a pair of lugs 38 and its leading edge slightly spaced from the lugs in advance thereof.

As each envelope being advanced by the conveyor leaves the forward ends of the chains, above the sprockets 33, it passes onto fingers 40 that serve to support the envelope as it passes into the bite between a gumming roll 41 and a cooperating pressure roll 42. The shaft 43 on which the sprockets 33 are mounted is connected by gearing 44 to a shaft 45 carrying the gumming roll 41, it being noted that the distance between the vertical plane X—X of the axis of shaft 43 and the vertical plane Y—Y of the axis of shaft 45 is slightly less than the width of an envelope 21.

Thus the leading edge of the envelope 21 enters the bite of the gumming rolls 41 and 42 before the trailing edge of the envelope has left the conveyor. Therefore, a pair of lugs 38 are still pressing on the envelope's trailing edge as the gumming rolls take hold, with a resulting tendency to buckle the envelope as the lugs 38 swing downwardly around the end of the conveyor.

In order to overcome this tendency, the fingers 40 are mounted on a pivot 46, so that turning of the fingers in a clockwise direction will cause them to lift the trailing edge of an envelope away from the lugs 38. The pivot 46 is connected by an arm 47 and linkage 48 to an operating lever 49 adapted to receive a reciprocatory movement from a cam 49a on the shaft 23 for each revolution of the feed wheel 22. This movement of the lever 49 is so timed that the fingers 40 are turned about their pivot 46 just enough to disengage the trailing edge of an envelope from the lugs 38 immediately after the leading edge of the envelope enters between the gumming rolls, thereby preventing any buckling of the envelope.

The gumming roll 41 bears on the periphery of a roll 50 running in a tub 51 containing liquid adhesive, so that passage of an envelope between the rolls 41 and 42 serves to apply an even coating of adhesive to the under surface of the envelope. As an envelope is further advanced toward the drum 7 by the gumming rolls, it is positively stripped from the surface of the roll 41

by fingers 52 extending into grooves 53 provided in the periphery of the roll 41, see Fig. 5. These fingers 52 are very narrow and serve to guide the envelope in its movement beyond the gumming roll without blocking any appreciable amount of adhesive from the under surface of the envelope. The fingers 52 support the gummed envelope until its leading edge enters the bite between the applicator rolls 10 and 11 which, as previously pointed out, are spaced from the drum 7 sufficiently to maintain a section of strip 2 in a horizontal plane, substantially tangential to the periphery of the drum 7, in cooperation with plate 12.

The lower applicator roll 10 is mounted on a shaft 54 parallel to the gumming roll shaft 45, with the vertical plane Z—Z of the axis of shaft 54 displaced from the vertical plane Y—Y of the axis of shaft 45 a distance slightly less than the width of an envelope 21. The gear 44' on the shaft 45 is connected to a gear 55 on the shaft

70
75
76
77

54 by an idler 58, and since the gears 44' and 55 are of the same pitch diameter as the rolls 41 and 10, the rolls travel at the same peripheral speed. The shaft 8 carrying the feed drum 7, also carries a sprocket 57, the pitch diameter of which corresponds to the diameter of the drum, and a chain 58 connects the sprocket 57 to a sprocket 59 on the shaft 45, having the same pitch diameter as the gear 44'. As a result, the surface of the drum 7 is moving at a speed corresponding to the peripheral speed of the rolls 10 and 41.

As previously pointed out, the strip 2 passes upwardly from the guide 13 around the lower applicator roll 10, before passing onto the periphery of the drum 7 at the tangent point A. Consequently, each envelope 21, with its under surface gummed, is delivered by the gumming rolls into the bite of the applicator rolls at a speed substantially corresponding to the rate of travel of any point on the strip 2. Since the displacement between the axes of the shafts 45 and 54 is less than the width of an envelope, the leading edge of each gummed envelope is received between the applicator rolls 10 and 11 before its trailing edge leaves the bite of the gumming rolls 41 and 42. Thus, gummed envelopes successively delivered by the conveyor 30 are positively applied to the strip 2 at regular intervals corresponding to the spacing between successive severance lines 3 on the strip.

As each envelope 21 passes onto the strip 2 between the rolls 10 and 11, its gummed underside is pressed against the strip so as to cause an immediate adhesion thereto. However, shortly after the trailing edge of the envelope leaves the gumming rolls 41 and 42, the roll 11 is lifted slightly, so that the remainder of the envelope passes freely onto the strip, without being subjected to any force other than the pull of the leading portion that is already attached to the strip by the adhesion of the gummed face of the envelope. In this way, lifting of the upper applicator roll 11 relieves the strip 2 of any retarding force such as might result in damaging the perforations 5 by which the strip is fed around the drum 7. As previously pointed out, it is one of the objects of the invention to attach the envelopes to the strip without subjecting it to any strain, such as might damage the perforations of the feed band 4 that are subsequently depended upon to carry the strip and its envelopes into the mechanism of a business machine, or other similar device.

In order to obtain the above described lifting, the roll 11 is mounted between the free ends of the arms 60, turnable with a shaft 61. The shaft 61 carries an operating arm 62 that is adapted to be turned by a lever 63 under the control of a cam 64 mounted on the shaft 23. A spring 65 pulling on an extension 66 carried by the shaft 61, tends to urge the roll 11 in the direction of the cooperating roll 10, so that the leading portion of a gummed envelope passing onto the strip, is pressed firmly into engagement with the strip. However, after about one-quarter of the envelope has engaged the strip, and the trailing edge has cleared the gumming rolls, the cam 64 causes the lever 63 to turn the shaft 61 in a clockwise direction, just enough to lift the roll 11 from pressure engagement with the envelope. Obviously, the above described operation of the roll 11 is repeated as each envelope arrives at the applicator rolls, since the cam 64 is mounted on the same shaft 23 that carries the feed wheel 22.

It is to be noted that the tangent point A on the drum 7 is displaced from the axis vertical plane Z-Z of the axis of the applicator roll shaft 54 a distance greater than the width of an envelope, so that the entire gummed surface of an envelope is completely in engagement with the strip by the time it reaches the drum. In order to insure that the envelopes will not tend to curl away from the strip as they pass around the drum 7, one or more flexible elements 67 carried by the shaft 61, extend freely around the drum from which they hang downwardly, so that the envelopes pass under these elements 67 before arrival at the tangent point A. If desired, suitable weights 68 can be attached to the ends of the elements 67, so that the latter exert just the right amount of dragging to insure adequate adhesion of the envelopes to the strip by the time the completed strip leaves the drum 7.

To prevent the completed strip from following around beneath the drum, by reason of the engagement of the pins 9 in the perforations 5, a stripping finger 69 is provided between the under side of the strip and the drum. The finger 69 is mounted on an adjustable bracket 70, so that the finger can be located at just the point where it will remove the strip from the pins before the pins exert any appreciable pull on the perforations, such as would tend to carry the strip around the under side of the drum. Therefore, as the strip with the envelopes thereon leaves the drum 7 and moves downwardly, it progressively resumes in its descent its previous fan-folded form on a suitable support 71 below the drum. That is to say, the interruption and guidance afforded by the support 71, in the path of the progressively descending strip, causes the composite web-and-envelope structure to fold on the score lines 3-3 into a zig-zag or fan-fold assembly of the same general form, as shown on the support 1, see Fig. 1.

From the foregoing, it is apparent that by the present invention, I have provided a highly efficient means and method for producing, for use in "business" machines, zig-zag or fan-folded assemblies or stacks of series-connected envelopes, the same involving the continuous feed or advancement of a cross-scored carry strip and simultaneously the synchronized feed and delivery in registered position on said strip of complete envelopes, gummed on their flap-carrying faces and traveling at the same speed at which the strip is traveling. While for purposes of illustration the under sides of the envelopes are gummed, prior to their delivery to the strip, the invention is not so limited, since the upwardly moving side of the strip nearest the gum tub could readily receive an application of adhesive. Furthermore, pre-gummed strip, or envelopes, can be employed that would only require moistening prior to the delivery of the envelopes to the strip.

I claim:

1. Apparatus for producing a zig-zag stack or assembly of series-connected envelopes, each with a closure flap as an extension from one of its faces, comprising a feed belt or conveyor having spaced projections for edgewise engagement with such envelopes, to effect a positive feed of a succession of same in predetermined spaced relation, means for continuously feeding lengthwise, at substantially the same speed as the so-fed envelopes, a paper web or strip having cross-scores of slightly greater spacing than the leading and trailing edges of each so-fed envelope,

means for merging the respective lines of web and envelope feed to oppose each envelope's flap-carrying face with the web face, means effective prior to such merger for applying adhesive to one of said opposed faces, the said two feeding means being synchronized to effect the registration of successive envelopes with successive web areas between the cross-scores, and means operable thereafter on the composite web-and-envelope structure produced by adhesion of said faces for assembling same progressively in a zig-zag stack on hinges or fold lines provided by said cross-scores between successive envelopes.

2. Apparatus for producing a zig-zag stack or assembly of series-connected envelopes, comprising means for continuously feeding a succession of envelopes in spaced relation by positive engagement with each envelope along an edge thereof, means for continuously feeding lengthwise, at substantially the same speed as the so-fed envelopes, a paper strip or web having cross-scores slightly farther apart than the leading and trailing edges of each so-fed envelope, means for synchronizing the web and envelope feeds and for effecting their merger in a common line of feed to oppose each envelope, by the face which carries its closure flap, in register with an area of the web face between adjacent cross-scores, and means operating prior to such merger for applying adhesive to one or the other of said sets of face areas, whereby to obtain by the adhesive union of successive advancing envelopes with said web, a continuous composite web-and-envelope structure adapted for zig-zag stacking on hinges or fold lines afforded by said cross-scores between said envelopes.

3. The herein described method of producing

a zig-zag stack or assembly of series-connected envelopes, which consists in continuously feeding lengthwise a paper strip or web having cross-scores at regular intervals, continuously feeding 5 at the same speed by positive edgewise engagement, a succession of envelopes, each slightly narrower than the spaces between said cross-scores, merging the respective lines of web and envelope feed, to bring into opposition with the web face, between its cross-scores, the successive envelope faces which carry the envelopes' closure flaps, applying successively to one set of said opposed face portions, before such merger, adhesive coatings over substantially the entire areas 10 thereof, and finally procuring the zig-zag stacking of the composite web-and-envelope structure thus formed on the hinges or fold lines provided by said cross-scores.

4. The herein-described method of producing 20 a chain or strip of series-connected envelopes, adapted for zig-zag or fan-folded stacking, which consists in feeding a succession of complete envelopes in spaced relation, feeding at the same speed a continuous web, having cross-scores defining areas each slightly wider than said envelopes, with a face of said web opposing the 25 envelope faces that carry the envelopes' closure flaps, applying adhesive to one set or the other of such opposing faces, and then merging the 30 respective lines of web and envelope feed to register and contact each envelope by its said face with a face portion of the web between said cross-scores, whereby to produce a composite web-and-envelope structure that is freely foldable in zig-zag fashion on said cross-scores.

VINCENT E. HEYWOOD.
